UNITED STATES PATENT OFFICE.

JAMES KELLEHER, OF CHIPPWA, ONTARIO, CANADA, ASSIGNOR TO HARPER ELECTRIC FURNACE CORPORATION, A CORPORATION OF NEW YORK.

ELECTRIC FURNACE.

Application filed July 17, 1925. Serial No. 44,183.

This invention relates to electric furnaces of the type which employ carbonaceous resistors and particularly to an improved construction of such furnaces whereby deterioration of the resistors employed is minimized. It has been found that if the resistor in such furnaces is surrounded by refractories such as silica brick, fire-clay brick or other refractory containing silicon in a silicate or other form, these silicates at high temperatures will decompose and silicon vapors will attack the carbonaceous resistor, forming thereon silicon carbide, and this causes deterioration of the resistor. This action may take place at comparatively low temperatures, the temperature at which it takes place being largely dependent upon the refractory surrounding the resistor and upon atmospheric conditions existing in the neighborhood of the refractories.

The major object of the present invention is to prevent such deterioration by providing a protective inner lining for the refractories forming the walls of the resistor chamber. Other objects will appear from the following description, taken in connection with the accompanying drawing, wherein

Fig. 1 represents a horizontal section 30 through the furnace resistor chamber, and Fig. 2 a fragmentary section through the roof of the furnace taken on the line 2—2 of Fig. 1.

In the drawings, 1 represents the outer walls of the furnace, 2 a resistor chamber containing a resistor formed of some carbonaceous material. 4 is an inner lining for the resistor chamber composed of Acheson graphite or some other carbonaceous material in the form of plates, and 5 is the roof of the resistor chamber composed of the same material as the plates 4. If desired

the floor of the chamber 2 may also be formed of graphite plates but in the form I have shown, the floor is formed of a septum 10 which may be composed of silicon carbide. The plates forming the lining 4 are preferably surrounded by material shown at 6, which forms a packing between the plates 4 and the refractory walls 1. The material 6 is preferably amorphous silicon carbide, as also is the covering 7 of the roof. The amorphous silicon carbide employed is preferably a powder which can be packed around the plates 4. This material is stable up to a temperature above 2000° C. and the silicon contained in this material will not be liberated until an extremely high temperature has been reached. By varying the thickness of the packing 6 between the plates 4 and the walls 1, the danger of silicon vapors entering into the resistor chamber 2 from the silicious refractories in the walls 1 is practically eliminated.

I claim:

1. An electric furnace comprising end and side walls of refractory silicon material enclosing a chamber, a carbonaceous resistor extending through said chamber from end to end, an inner lining of carbonaceous material surrounding said resistor and forming a chamber therefor, and a packing between the inner lining and the outer wall of sufficient thickness to avoid entrance of silicon vapor from said walls into said resistor chamber.

2. An electric furnace formed with a chamber having walls formed of refractories containing silicon and an inner lining for said walls comprising plates of carbonaceous material, and a packing of amorphous silicon carbide between said plates and refractories, and a carbonaceous resistor in said chamber.

JAMES KELLEHER.
